COTTON PICKER SPINDLE AND DOFFER
MECHANISMClarence R. Hagen and Louis E. Nickla, Memphis,
Tenn., assignors to International Harvester
Company, a corporation of New Jersey

Application June 30, 1951, Serial No. 234,488

6 Claims. (Cl. 56—41)

1

This invention relates to cotton picker mechanisms of the rotating spindle type and more specifically to a novel improvement in the doffing stage thereof.

In such machines currently in use, the practice has been to mount the spindles with the upper edges of their conical picker portions positioned to move in a plane parallel to or coplanar with the bottom side of an associated doffer element. Such an arrangement was believed to provide the ultimate in doffing efficiency on the theory that the doffer element would sweep uniformly across the entire length of the cone and thus brush it clean. The theoretical desirability, however, is not available in actual practice. The cotton lint distributes unevenly along the cone and is wound more times at the tip of the cone than at its base. The cumulative pressures of overlaying windings anchors the lint most tightly to the tip of the spindle which, to obtain complete doffing, demands more effort to dislodge the fibers from the tip than the base section.

Doffing of the spindles in current designs is further complicated by wear of the support bearings which causes the spindles to droop or sag at the tip away from the sweeping face of the doffer so that progressively less and less pressure is obtained towards the tip of the spindle and increased towards the base of the cone.

A general object of the invention is to arrange the spindles and doffers in such manner that progressively increased pressures are obtained by the doffers on the lint as it is being swept towards the tips of the spindles thus assuring a clean sweep thereof.

More specifically the invention contemplates arranging the spindles with their upper edges in converging relationship with the plane of the sweeping face of the doffer in a direction towards the tips of the spindles when the spindles and doffer are in superposed relationship.

A still further object is to dispose the peripheral surfaces of the spindles at a sufficient angle with respect to the sweeping face of the doffer to insure convergence between the top edges of the spindles and the doffer face thereabove during substantially the entire effective life of the spindle bearings to compensate for drooping as the spindle bearings wear.

A further object is to provide an arrangement which may be incorporated in existing machines without any modification of associated parts.

These and other objects of the invention will become more apparent from the specification and the drawings, wherein:

2

Figure 1 is a fragmentary side elevational view partially in vertical section taken along line 1—1 of Figure 2 of a portion of a cotton picker assembly illustrating the relative disposition of the spindles and doffers in accordance with the invention, and

Figure 2 is a fragmentary plan view thereof, partly in section, to show the relative horizontal positions of the spindles with respect to the related doffing element.

Describing the invention in detail, the picker drum generally designated 2 is illustrated as comprising several upright carrier elements or bars 4, 4 each supporting a plurality of laterally extending spindle assemblies 6, 6. The carriers and general arrangement of the construction shown may be in accordance with U. S. Patent 2,140,631.

Each spindle assembly 6 includes a nut 8 with a bearing 9 therein sleeved over a shank 10 of a spindle 12, the nut being threaded into the related bar 4 within an aperture therein to secure the spindle assembly thereto. This construction may be such as shown in U. S. Patent 2,497,776. A guard cap 14 may be sleeved on the shank and secured thereto as by press fitting or pinning outwardly of the nut 8.

Each spindle 12 comprises at the outer end of its shank 10, a conical picker or plant-entering portion generally indicated 16, and provided with a plurality of lint-snagging barbs 18, 18 along its length.

Each of the spindles 12 is mounted at an angle and tilted upwardly with respect to the carrier bar on which it is mounted, and it will be seen from Figure 1 that the upper edge of each spindle portion 16 converges towards its tip with the bottom doffing or sweeping face 20 of a related doffer element 22 disposed thereabove in vertical registry therewith. Preferably, the upper edge of each portion 16 is spaced adjacent to its tip about $\frac{1}{64}$ of an inch below the related face 20 and adjacent to the base of the cone about $\frac{3}{64}$ of an inch.

Referring now to Figure 2, the drum 2 rotates on a vertical axis (not shown) in a counter-clockwise direction as shown by the arrow. The doffer elements 22 are keyed to a vertical shaft 24 constituting support means for the doffer elements. Each of elements 22 includes an annulus 26 providing a plurality of doffing surfaces which describe the annular bottom doffing face 20 during rotation of the shaft which proceeds counter-clockwise in the direction of the arrow. It will be understood that the corresponding spindles on each of the bars are arranged in circumferential

rows so that each spindle successively approaches and passes through the doffing station.

In order to facilitate doffing, the spindles are arranged on the oscillating bars whereby each bar may be angled horizontally as the spindles approach the doffing station to dispose the spindles into trailing position with respect to the direction of rotation of the drum structure as shown in Figure 2. In this location the spindles are moving generally endwise in their endless generally horizontal path. The spindles are then brought into more or less tangential relation with respect to the doffer element, as best shown by the lowermost spindle in Figure 2. With the doffer element moving in the counter-clockwise direction of the arrow in Figure 2, the doffer stripping means 29 contacts the cotton at the tip of the spindle first, thus removing it and out of the way of cotton wound on the spindle further from the tip. The doffing element progressively passes over the spindle toward its inward end and engages the cotton thereon and sweeps it towards the free end of the spindle. The rotation of the doffer is faster than and in the same direction as the spindles as shown by arrows in Figure 2 so that the cotton fibers wound on the spindle are partially unwound therefrom and pushed or brushed towards and off the narrow ends of the spindles as more fully explained in applicants' U. S. Patent 2,247,686. The positioning of the periphery of each spindle in converging relationship towards its tip with the plane of the sweeping surface of the doffer develops increasing pressures towards the tip of the spindle, that is, the cotton is progressively compressed as the doffing approaches the tip of the spindle. This realizes the necessity for applying pressures in proportion to the need. In addition, drooping of the spindle due to wear of its support bearing will not materially change this relationship especially since the doffers are adjustable vertically.

It will be understood that novel relationship between the spindles and doffers may be applied to existing equipment by locating new spindles on the axes of the old and forming the new spindles with picking cones which have a reduced conical angle or angle of taper.

What is claimed is:

1. In apparatus for doffing cotton from a free ended spindle by co-operatively associated surface of a doffing element wherein the surface is disposed in sweeping relationship to the spindle to remove the cotton therefrom toward said free end thereof, the improvement comprising: said surface and the opposed edge portion of the spindle disposed in converging relationship toward the free end of the spindle in the superposed positions of said spindle and said surface.

2. In apparatus for doffing cotton from a free ended cotton picker spindle by a co-operatively associated doffer surface wherein the surface is disposed alongside an opposed longitudinal edge of the picker spindle in sweeping relationship thereto and relatively movable therewith in directions for removing cotton from the spindle toward the free end thereof, the improvement described in the doffing position of said spindle and doffer surface comprising: said edge of the picker spindle disposed closer to said surface at said free end than elsewhere.

3. The combination with a rotatable doffer having a planar doffing face disposed substantially

perpendicular to the axis of rotation of the doffer, of a free ended cotton picker spindle of a type adapted to wind cotton thereon and rotatable on the longitudinal axis thereof, said longitudinal axis disposed angularly to the axis of rotation of the doffer, said spindle positioned with an edge thereof cooperatively associated with the face in opposed closely spaced relationship thereto, in the doffing positions of said face with said spindle said edge converging with said face toward the free end of the spindle and adapted to progressively increase pressure on the cotton with said face as said cotton is being swept off the spindle toward said free end.

4. For use in a cotton picking machine having free ended picking spindles rotated about their individual axes while being swept through an endless generally horizontal path, doffing means for doffing cotton from such spindles and comprising a doffer element having a bottom doffing face, and means for rotatably supporting said doffer element above said path in vertical registry with a portion of said path and said spindles in said portion as they sweep therewith and with said face generally horizontal and opposing and closely spaced above the upper edges of the spindles in said portion, and means for supporting the spindles with their upper edges tilted upwardly toward their free ends in converging relationship toward said bottom face in planes transverse thereto as each spindle is disposed in vertical registry with said face.

5. For use in a cotton picking machine having free ended picking spindles rotated about their individual axes while being swept through an endless path, doffing means including stripping means for removing cotton from the spindles, and means for supporting said doffing means contiguously to said path in transverse registry therewith tangentially of the surface of the spindles, and with said stripping means in sweeping relationship to said surface in the doffing position of each spindle with said stripping means, said stripping means and said spindles formed and arranged to develop increasing pressures on the cotton therebetween as it is being swept off toward the free ends of the spindles in said doffing positions thereof.

6. For use in a cotton picking machine having conical picking spindles tapering toward free ends thereof and rotatable about their principal axes while being swept endwise substantially in a horizontal plane, a doffing apparatus co-operatively associated with such spindles for doffing cotton therefrom and comprising a doffer element rotatable on a generally vertical axis and having sweeping-face-means with means rotatably supporting said doffer element flatwise of and contiguous to the plane of the spindles and with said sweeping face-means diagonally related to said spindles toward their free ends and disposed in vertical registry with and closely spaced from the spindles as they sweep therewith in the doffing positions thereof.
